UNITED STATES PATENT OFFICE

170,190

LIVING ROOM SOFA

Henry P. Glass, Chicago, Ill., assignor to The William Brenner Furniture Corp., Cincinnati,
Ohio, a corporation of Ohio

Application April 24, 1953, Serial No. 24,662

Term of patent 3½ years

(Cl. D15—11)

To all whom it may concern:

Be it known that I, Henry P. Glass, a citizen of the United States, residing at Chicago, Cook County, Illinois, have invented a new, original, and ornamental Design for a Living Room Sofa, of which the following is a specification, reference being had to the accompanying drawing, forming a part hereof.

The single figure is a front perspective view of a living room sofa, showing my new design.

I claim:

The ornamental design for a living room sofa, as shown.

HENRY P. GLASS.
